UNITED STATES PATENT OFFICE.

WILLIAM H. ABEL, OF BRISTOL, NEW HAMPSHIRE.

IMPROVEMENT IN METHODS OF CONSTRUCTING LOOP-WHEELS FOR KNITTING-MACHINES.

Specification forming part of Letters Patent No. **171,908**, dated January 11, 1876; application filed June 7, 1875.

To all whom it may concern:

Be it known that I, WILLIAM H. ABEL, of Bristol, in the county of Grafton and State of New Hampshire, have invented an Improvement in the Construction of Knitting-Machine Attachments; and I do hereby declare that the following is a full and exact description thereof, reference being had to the accompanying drawings, making part of this specification—

Figure 1 being an axial section of the improved attachment; Fig. 2, a perspective view of the same.

Like letters designate corresponding parts in both figures.

My improvement consists in an improved construction of the loop-wheels of circular-knitting machines for closing the barbs of the alternate needles, so that they shall not take stitches when passing the loop-wheel in knitting with two threads of different colors, two of these loop-wheels, one for each color of thread, acting, respectively, on the alternate needles. The usual construction of the wheels to effect this purpose consists in filling out the alternate needle-spaces in the wheel sufficiently to close the barbs of the alternate needles entering therein. The main difficulty lies in producing a uniform filling in the several alternate spaces, and by simple and cheap means. By my construction this is effected in a very perfect and simple manner, as follows:

The wheel being made of a central tubular box or bearing, *a*, over which a ring or collar, *b*, is secured, both parts also being finished in a lathe, the part first is formed with a ridge or bead, *c*, turned accurately, and with uniform projection for the needle-barbs to press against. Then, in the alternate spaces between the hook-plates *d d*, this ridge *c* is filed or cut away, as shown, to allow the other alternate needles to work freely, and take stitches as they pass the wheel. Thus a simple and very accurate and perfectly uniform set of projections is produced.

What I claim as my invention, and desire to secure by Letters Patent, is—

The improvement in the method of constructing the loop-wheels for circular-knitting machines herein described, consisting in first turning a peripheral ridge or projecting bead, *c*, thereon, and then cutting or filing away the same in the alternate spaces between the hook-plates, substantially as and for the purpose herein specified.

Specification signed by me this 2d day of October, 1874.

WM. H. ABEL.
